UNITED STATES PATENT OFFICE.

HOWARD R. LEVICK, JR., OF LEXINGTON, KENTUCKY.

ARCH SUPPORT.

Application filed December 18, 1925. Serial No. 76,336.

This invention relates to improvements in arch supports and has for an object the provision of a device of this character which will support the arch of the foot and also provide a foot bandage.

Another object of the invention is the provision of a device of the above character which includes removable pads, so that the support may be adjusted as desired, means being provided for securing the support to the foot, which will also act to hold the pads in place.

With the above and other objects in view, the invention further includes the following novel features and details of construction, to be hereinafter more fully described, illustrated in the accompanying drawings and pointed out in the appended claim.

In the drawings:—

20 Figure 1 is a perspective view illustrating the invention applied.

Figure 2 is a fragmentary plan view of the pocket.

25 Figure 3 is a perspective view showing the invention removed from the foot.

Figure 4 is a view similar to Figure 3 but showing the pocket arranged to receive or remove the pads with the latter illustrated removed from the pocket.

30 Referring to the drawings in detail wherein like characters of reference denote corresponding parts, the improved support comprises a pocket 10 which is shaped to fit beneath the arch of the foot and which includes side walls 11 and 12, the latter being designed to be placed next to the foot. The walls 11 and 12 are secured together along their curved side edges 13, while their other edges 14 and 15 are unattached, the latter forming the opening or mouth of the pocket.

35 The pocket 10 is designed to removably receive one or more substantially wedge-shaped pads 16, which, when placed in the pocket provide an arch support capable of 40 being regulated as desired.

The wall 11 of the pocket is extended

beyond the edge 14 and secured to this extended portion is one end of an elastic strap 17. The thickness of this strap is substantially the same as the thickness of the wall 50 12 so that a substantially flush surface is provided for contact with the foot.

The opposite end of the strap 17 is secured to a tab 18 which is formed by a reduced extension of the wall 11 and as the 55 wall 11 forms the lower wall of the pocket or support, the adjacent portion of the strap 17 will extend across the opening or mouth 15 and close the latter so as to hold the pads 16 in place. The pads may be readily removed or inserted by arranging the strap as shown in Figure 4 of the drawings.

The invention is susceptible of various changes in its form, proportions and minor details of construction and the right is here- 65 in reserved to make such changes as properly fall within the scope of the appended claim.

Having described the invention what is claimed is:—

70 An arch support embodying a pad designed to be positioned beneath the foot and including a pocket having a narrow inner end and a relatively wide outer open edge, the opening being co-extensive with the 75 width of the pocket and the pocket tapering towards its narrow end, a tab formed integral with and extending from the lower edge of the pocket opening and located centrally of the mouth of said pocket and having its side edges terminating a relatively 80 short distance from the ends of the pocket opening, an elastic strap having one end secured to the narrow end of the pocket and its opposite end extending over the pocket 85 and secured to the tab to provide combined means for closing the pocket and securing the support to the foot, and a wedge-shaped pad adapted to be removably positioned in said pocket and held therein by the tab. 90

In testimony whereof I affix my signature.

HOWARD R. LEVICK, JR.
